UNITED STATES PATENT OFFICE.

KENTON CHICKERING, OF OIL CITY, PENNSYLVANIA.

DESIGN FOR A BASE FOR PUMPING POWER.

SPECIFICATION forming part of Design No. 30,698, dated May 2, 1899.

Application filed March 20, 1899. Serial No. 709,855. Term of patent 14 years.

To all whom it may concern:

Be it known that I, KENTON CHICKERING, a citizen of the United States, residing at Oil City, in the county of Venango and State of Pennsylvania, have invented and produced a new and useful Design for a Base for Pumping Power, of which the following, taken in connection with the accompanying drawing, is a full and exact description.

10 The drawing illustrates in perspective a base for pumping power having a form or configuration which embodies my design.

The base-plate which embodies my design has the form of a parallelogram, made up of 15 side bars 1 1 and end bars 2 2, divided centrally by a bar 3, arched or raised, as at 4, and at said point expanded into a hollow por-

tion or box 5, which is shouldered, as at 6, and in line with said raised box 5 are two pedestals or pillars 7 and 8.

20 The leading or material feature of my design consists of the base, provided with the central bar 3, broken at intervals by the raised or elevated box 5 and the pillars 7 and 8.

Having described my invention, what I claim as new, and desire to secure by Letters Patent, is—

The design for a pumping-power base, as herein shown and described.

KENTON CHICKERING.
